TELEPHONE SYSTEM

Filed May 13, 1930

UNITED STATES PATENT OFFICE

JOHANNES STICH, OF BERLIN, GERMANY, ASSIGNOR TO SIEMENS & HALSKE AKTIEN-
GESELLSCHAFT, OF SIEMENSSTADT BEI BERLIN, GERMANY

TELEPHONE SYSTEM

Application filed May 13, 1930, Serial No. 452,087, and in Germany June 6, 1929.

For telephone systems with several exchanges and automatic working it is known that the connections extending over several exchanges are completed by an operator in 5 the exchange to which the wanted station is connected. When now in the exchange of the wanted subscriber there are separate connecting devices provided for local calls between subscribers of the exchange and for 10 calls coming from other exchanges, difficulties occur when the switches, over which the incoming calls extend, instead of being positioned by number impulses, are positioned 15 by designating the contact of the wanted line, for which the switch hunts.

Difficulties occur more especially if, when 20 an incoming call is set up and the wanted subscriber's line is engaged, the existing connection must not be affected at first, this for example being the case when, as in private 25 branch exchanges, the value of the existing connection cannot be ascertained forthwith, because the switches cannot or must not be provided with correspondingly arranged testing devices.

Now the invention enables incoming calls 30 to be made fully effective in particularly suitable, simple and reliably operating manner, because after the wanted line has been designated by the operator, the switching operations for reaching the wanted subscriber's line, that is to say for example the positioning of the wipers of the switch onto the 35 stationary bank contacts, and the ascertaining of the engaged condition of this line are effected over separate switching members of the switch.

The arrangement according to the invention 40 offers quite a number of technical and economic advantages. For example it is unnecessary to provide the subscribers' lines with special signals whereby before completing incoming connections the operator can 45 recognize the engaged condition of the wanted subscriber's line.

Furthermore, when existing systems having 50 only one exchange are extended by the erection of additional exchanges it is possible to let the junction traffic between the

exchanges be supervised by an operator without any alteration of the existing plant.

By suitably carrying out the invention it is also possible, when the wanted subscriber's station is engaged, for the operator, who sets up the incoming call, to communicate 55 over the positioned switch with the speaking subscribers for the purpose of releasing the existing connection, thus in these cases it is 60 not necessary to set up a separate connection between the operator and the engaged subscriber.

As an example of the invention, the drawing 65 shows an arrangement for telephone private branch exchanges with stepping switches, but the invention is not limited thereto, and it can also be used for other systems. Furthermore, in place of stepping switches can be used other kinds of switches 70 for example relay switches.

From the drawing have been omitted all 75 details that are not required for understanding the invention. Thus for example of the connecting devices in the private branch exchange HV is only shown a call seeker AS1 by its three wipers a_2, b_2, c_2 , the test relay P_{as} and the feeding bridge relay A1. Likewise have been omitted those devices that are required for calls from the subscribers of 80 the exchange HV to other exchanges.

The arrangement functions in the following 85 manner: When a subscriber of the main exchange SA wishes to be connected to the private branch exchange subscriber N, the relay A is energized by the ringing current flowing over the main exchange line. On being operated, the relay A closes its contact 1 a and thus connects up the calling lamp AL and winding I of the relay H over: 90 earth, contact 1 a , winding I of relay H and parallel thereto lamp AL, battery, earth. On being operated, relay H closes the contacts 2 h and 3 h , thereby at contact 2 h it prepares the circuit for energizing the test relay P 1, and at contact 3 h it closes a locking circuit for itself over: earth, contacts 3 h, b , winding I of H, battery, earth. The lighting of the lamp notifies the operator 95 that a main exchange call has arrived. 100

Thereupon she throws the speaking key AT and answers the call.

The throwing of the speaking key AT closes a circuit over: earth, battery, contact 4 *at* of the key AT, winding II of relay H, winding I of relay U, contact 5 *p 1*, relay B, earth. In this circuit the relay H locks itself and the relays B and U are operated. By opening its contact 6 *b*, the relay B interrupts the circuit of the lamp AL, which is thus extinguished. Relay U at its contact 7 *u* closes a locking circuit for itself over: earth, relay B, contact 7 *u*, winding II of relay U, contact 8 *v*, cut-off key TrT, battery, earth. Furthermore, at its contact 9 *u* it prepares the locking circuit for winding I and the short circuiting of winding II of the test relay P 1. The operator then presses the key NT associated with the wanted extension station subscriber and thereby closes the energizing circuit for the rotary magnet D of the switch WL over: earth, contact 10 *nt* of the extension station key MT, contact 11 *at* of the speaking key AT, contacts 12 *tr* and 13 *p 1*, magnet D, interrupter RU, battery, earth; whereupon the switch is started up.

When its wipers reach the contact, which has been designated in the contact bank of the switch WL by the operator pressing the key NT and to which the wanted subscriber's line is connected, the relay Tr is operated over: earth, contact 14 *nt* of the key NT, wiper *d* of the switch WL, winding I of relay Tr, contact 15 *at* of the key AT, battery, earth. By closing its contact 16 *tr*, the relay Tr closes a locking circuit for itself over: earth, relay B, contacts 5 *p 1*, 16 *tr*, winding II of relay Tr, cut-off key TrT, battery, earth; and at its contact 12 *tr* it opens the circuit of the rotary magnet D. Thereby the switch WL is arrested when it reaches the line of the wanted subscriber, and it can be seen that this is done independently of the fact that the subscriber is free or is engaged. The relay Tr also short circuits winding II of relay H at its contact 17 *tr*, so that H falls back slowly.

If the subscriber be free, relay P 1 is operated over the following circuit during the time H takes to fall back: earth, contacts 2 *h*, 18 *tr*, windings II and I of relay P 1, wiper *c* 3 of switch WL, winding II of relay T, battery, earth. Relay P 1 opens its contact 13 *p 1* in order to prevent the switch starting up again when relay Tr falls back. It also short circuits its high resistance winding II at contact 19 *p 1*, and thus marks the subscriber's line engaged. Furthermore, by opening its contact 5 *p 1* and closing contact 20 *p 1*, the relay P 1 connects up the relay P 2 over: earth, relay B, contact 20 *p 1*, relay P 2, battery, earth. Relay P 2 closes its contact 21 *p 2*, thereby establishing a circuit for the lamp ML over:

earth, battery, lamp ML, contact 21 *p 2*, wiper *d* of the switch WL, contact 14 *nt*, earth. Therefore, the lamp ML continues to burn as long as the key NT is pressed by the operator, whereby she recognizes that the wanted subscriber is free. On being operated, the relay P 2 also closes the contacts 22 *p 2* and 23 *p 2*, therefore, after the key AT has been released, the ringing current, which has been applied to the lead *a 3* over contact 24 *u* when relay U was operated, reaches the subscriber with interruptions. The calling of the subscriber is notified to the operator by the flashing of the lamp BL, the circuit of which is closed at contact 25 *u* and extends over: earth, interrupter RU, contact 25 *u*, lamp B1, contact 26 *at* of the speaking key AT, battery, earth.

When the subscriber N takes down his receiver, relay S is operated over: earth, winding II of relay S, contact 27 *at* of the key AT, contact 23 *p 2*, wiper *b 3* of the switch WL, subscriber's station N, wiper *a 3* of the switch WL, contact 22 *p 2*, contact 29 *at* of the key AT, contact 24 *u*, interrupter RU, source of alternating current W, battery, earth. Relay S at its contact 30 *s* closes the circuit of relay V over: earth, contact 30 *s*, relay V, battery, earth. Relay V opens the locking circuit of relay U by opening its contact 8 *v*, whereupon U falls back and switches off the ringing current from lead *a 3* by moving the contact 24 *u* back into the position 31 *u*. The falling back of relay U also returns the contact 25 *u*, so that the following circuit is established for the lamp BL: earth, battery, contact 26 *at*, lamp BL, contacts 32 *u*, 35 *b*, earth. The lamp BL, therefore, burns continuously and this notifies the operator that the subscriber N has answered. On being operated, the relay V has also closed the contact 34 *v*, so preventing, on the falling back of relay U and the opening of contact 9 *u*, the circuit for the test relay P 1 being opened. As furthermore the contacts 35 *v* and 36 *v* were closed when relay V was operated, the connection between the main exchange subscriber and the extension station subscriber has now been established.

The release of the connection is effected in the following manner: Relay S falls back when the extension station subscriber hangs up his receiver. The opening of the contact 30 *s* interrupts the circuit of relay V, which on falling back opens at contact 34 *v* the circuit of relay P 1 and at its contacts 35 *v* and 36 *v* opens the leads *a 3* and *b 3*. By the falling back of P 1 is released the contact 20 *p 1*, thus deenergizing relay P 2, which opens its contacts 21 *p 2*, 22 *p 2*, 23 *p 2*. Furthermore, the circuit of relay B is opened at contact 20 *p 1*, so that it also falls back and opens its contact 33 *b*; this causes the lamp to go out and the operator

is thereby notified that the conversation has been ended.

If the subscriber be engaged, the circuit changes take place as above described till the energizing of relay T_r . But now the relay P_1 and, therefore, also P_2 are not operated, as relay P_{as} is energized and has closed its contact $37\ pas$, hence the high resistance winding of this relay is short circuited and the relay P_1 in parallel therewith does not receive sufficient current to be operated. Therefore, the contact $38\ tr$ is closed, but contact $21\ p_2$ is open. Hence the following circuit for lamp ML is established: earth, battery, lamp ML , contact $38\ tr$, interrupter RU , earth. The lamp, therefore, flashes, so notifying the operator that the subscriber is engaged. Thereupon the operator throws the key RS and is thus connected to the subscriber N over the following route as the contact $39\ tr$ is closed: earth, condenser K , contact $40\ rs$ of the key RS , operator's head set Abf , contacts $41\ rs$ of key RS , $42\ at$ of key AT , $39\ tr$, wiper $b\ 3$ of the switch WL , subscriber N , lead $a\ 1$, lead $a\ 2$, wiper $a\ 2$ of the call seeker $AS\ 1$, feeding bridge relay $A\ 1$, battery, earth. She then informs the wanted subscriber that there is a main exchange call for him. In the mean time relay H has fallen back and opened contact $2\ h$, because its second winding has been short circuited over contact $17\ tr$ when relay T_r was operated. Thus the circuit of the test relay P_1 has been opened, so that, after the subscriber N has ended his conversation at the request of the operator, the test circuit for relay P_1 has to be again established. The operator, therefore, presses now the key T_rT and by thus interrupting the locking circuit over the second winding of relay T_r causes this relay to fall back; so that the opening of contact $17\ tr$ removes the short circuit from relay H , which is again operated and again closes contact $2\ h$. The operator then again operates the key NT , thus again operating the relay T_r and again initiates all the succeeding circuit changes as above described, so that the connection of the main exchange subscriber with the extension station subscriber is thereby again established in the same manner.

What I claim is:

1. In a private branch exchange, subscribers' lines, a trunk incoming from a main exchange and terminating in a switch having access to said lines, means for marking a called line, means for operating said switch to hunt for the marked line, two test wipers on said switch, means controlled over the first of said wipers for stopping the switch on the called line, and means controlled over the second of said wipers for determining the idle or busy condition of said line.

2. In a private branch exchange, sub-

scribers' lines, an incoming trunk terminating in a switch having access to said lines, means for marking a called line, means for operating said switch to hunt for said called line, a test relay for stopping said switch in engagement with said line, a second test relay for determining the idle or busy condition of said line, and a testing circuit including said second test relay closed by the operation of said first test relay.

3. In a telephone system, subscribers' lines, a switch having access to said lines, means for operating said switch to hunt for a called one of said lines, a test relay controlled over one wiper of said switch for stopping said switch in engagement with said called line, and a second test relay controlled over a second wiper of said switch for determining the idle or busy condition of said line.

4. In a private branch exchange, subscribers' lines, an incoming trunk terminating in a switch having access to said lines, an operator's position for intercepting incoming calls, means controlled by the operator for operating said switch to connect with a called line irrespective of the idle or busy condition of said line, and means for permitting the operator to converse with a busy called subscriber.

5. In a private branch exchange, subscribers' lines, a switch having access to said lines, an operator's position, means for operating said switch to hunt for a called line, a test relay for stopping said switch on the wanted line, a second test relay for determining the idle or busy condition of said line, and a signal at said operator's position jointly controlled by said test relays for informing the operator of the idle or busy condition of said line.

6. In a private branch exchange, subscribers' lines, a switch having access to said lines, an operator's position, means for operating said switch to hunt for a called line, a test relay for stopping said switch on the wanted line, a second test relay for determining the idle or busy condition of said line, and a circuit prepared by said first test relay for permitting the operator to converse with the called subscriber in case said line is found busy.

7. In a telephone system, subscribers' lines, an incoming trunk terminating in a switch having access to said lines, an operator's position for intercepting incoming calls, means for operating said switch to hunt for a calling line, two line wipers and two test wipers on said switch, a test relay controlled over one of said test wipers for stopping said switch on the called line, a second test relay controlled over the other test wiper for determining the idle or busy condition of said line, a signal at said operator's position jointly controlled by said test

relays to inform the operator of the condition of said line, and a circuit prepared by said first relay and including only one of said line wipers for permitting the operator to converse with the called subscriber in case said line is busy.

8. In a private branch exchange, subscribers' lines, a trunk line connecting said exchange with a main exchange, said trunk line terminating in an automatic switch in the branch exchange, an operator's position for intercepting incoming calls over said trunk line, means controlled by the operator for operating said switch into engagement with a called one of said subscribers' lines, and offering means whereby the operator can cut in on a busy line and inform the wanted subscriber of the main exchange call.

9. In a telephone system, a main exchange and a branch exchange, a trunk line connecting said exchanges and terminating in an automatic switch and an attendant's position at the branch exchange, subscribers' lines in said branch exchange, a signal at said attendant's position operated responsive to the extension of a connection from a main exchange subscriber's line to said trunk line, means controlled by the attendant for operating said switch to further extend the connection to a wanted branch exchange subscriber's line, and means for permitting the attendant to converse with a busy called subscriber.

In witness whereof, I hereunto subscribe my name this 21st day of March, A. D. 1930.

JOHANNES STICH.

CERTIFICATE OF CORRECTION.

Patent No. 1,812,222.

Granted June 30, 1931, to

JOHANNES STICH.

It is hereby certified that error appears in the printed specification of the above numbered patent requiring correction as follows: Page 4, after line 33, insert the following as claim 10:

10. In a branch exchange wherein local calls are completed by means of subscriber controlled automatic switches and wherein all incoming trunk calls are completed by an attendant by means of automatic switches individual to the incoming trunk lines, means for signalling the attendant when an incoming call has been extended to a line busy in another connection, and means controlled by the attendant for establishing a talking connection with the busy line over the apparatus used in extending the connection.

and that the said Letters Patent should be read with this correction therein that the same may conform to the record of the case in the Patent Office.

Signed and sealed this 6th day of October, A. D. 1931.

(Seal)

**M. J. Moore,
Acting Commissioner of Patents.**
